DISPLAY RACK

Theodore I. Youngquist, Loup City, Nebr.

Application December 1, 1949, Serial No. 6,354

Term of patent 3½ years

(Cl. D80—9)

To all whom it may concern:

Be it known that I, Theodore I. Youngquist, a citizen of the United States of America, residing at Loup City, in the county of Sherman and State of Nebraska, have invented a new, original, and ornamental Design for a Display Rack, of which the following is a specification, reference being had to the accompanying drawing, forming a part thereof.

In the drawing:

Figure 1 is a side elevational view showing my new design of a display rack,

Figure 2 is a view taken on the line 2—2 of Figure 1, looking downwardly towards the base of the rack,

Figure 3 is a top plan view.

I claim:

The ornamental design for a display rack, as shown.

THEODORE I. YOUNGQUIST.
